Primary Examiner — Elizabeth Albert*(74) Attorney, Agent, or Firm* — McCarter & English LLP**CLAIM**

The ornamental design for a reciprocating saw blade, as shown and described.

DESCRIPTION

FIG. 1 is a front perspective view of a reciprocating saw blade showing the present invention;

FIG. 2 is a side elevational view thereof;

FIG. 3 is a top view thereof;

FIG. 4 is a bottom view thereof; and,

FIG. 5 is a front elevational view thereof.

The broken lines in the drawings are included for the purpose of showing portions and edges of the reciprocating saw blade that form no part of the claimed design. The straight broken lines in FIGS. 1 and 2 extending from the top edge to the bottom edge of the reciprocating saw blade define the bounds of the claimed design and form no part thereof.
